UNITED STATES PATENT OFFICE.

ALFRED GRIEB, OF ELIZABETH, NEW JERSEY, ASSIGNOR TO THE SINGER MANUFACTURING COMPANY, A CORPORATION OF NEW JERSEY.

HAT-SEWING MACHINE.

1,283,501.

Specification of Letters Patent. Patented Nov. 5, 1918.

Application filed November 22, 1916. Serial No. 132,756.

To all whom it may concern:

Be it known that I, ALFRED GRIEB, a citizen of the United States, residing at Elizabeth, in the county of Union and State of New Jersey, have invented certain new and useful Improvements in Hat-Sewing Machines, of which the following is a specification, reference being had therein to the accompanying drawings.

This invention relates to sewing machines adapted for sewing sweat bands into hats, and it has for its object to provide convenient and effective means adapted to support a hat during the stitching operation and so constructed and arranged as to permit the easy introduction of the hat into stitching position and its easy removal therefrom after the completion of a stitching operation.

The improvement may be applied to the machine forming the subject of my Patent No. 1,206,433, issued November 28, 1916. In the machine disclosed in said patent, the hat-supporting disk is mounted between the presser- and feed-members but adapted to slightly adjust itself to inequalities in the material. In order to introduce a hat into stitching position in said machine, the hat-supporting disk and presser-member are moved away from the feed-member. To facilitate this operation I have now mounted the hat-supporting disk so that it can be swung away from operative position in a plane intermediate the presser- and feed-members, leaving a clear space for the introduction of a hat.

After the hat is placed in position between the feed- and presser-members, the hat-supporting disk is swung upwardly into operative position by actuating a knee- or foot-plate so as to leave the operator's hands free to adjust the hat. The hat-supporting disk is maintained in operative position by means of a spring-pressed latch.

When the stitching operation has been completed, the hat-supporting disk is thrown out of operative position by the release of its latch which is provided with a pushing finger or projection adapted to engage a shoulder on the disk-supporting lever and forcibly move the hat-supporting disk away from operative position to provide a clear space for the removal of the hat. The initial actuation of the latch may be supplemented by gravity in moving the hat-supporting

disk to extreme retracted position. When 55 the hat-supporting disk is in retracted position its carrier rests upon a stop provided for the purpose.

In the accompanying drawings, Figure 1 is a front elevation of the machine showing 60 the hat-supporting disk in both operative and inoperative positions, the latter position being indicated by dotted lines; Fig. 2 is a plan of the presser-arm partly in section, illustrating the mounting of the hat-support thereon and the mechanism for moving the hat-support into and out of operative position; Fig. 3 is a side elevation of the complete machine and Fig. 4 is a perspective view showing the supporting bracket and disk-supporting 70 lever.

As illustrated in the drawings, the base 1, bed-plate 2, casing 3, balance wheels 4, looper 5, feed-member or wheel 6, presser-member or wheel 7 and presser-arm 8 or support for 75 the presser-member, are all substantially like the parts of the machine described in my patent above referred to.

Secured to the presser-arm 8 by means of a set-screw 9 is a pin 10 upon which is 80 fulcrumed a horizontally disposed bracket 11 having a lateral arm entered by a screw-stud 12 upon which is pivotally mounted an upwardly extending plural-armed lever or carrier 13 having near its upper end a 85 spherical-headed or ball-stud 14 embraced by cap-pieces 15 secured by screws or otherwise to the hat-supporting disk 16 having its periphery in a plane intermediate the feed and presser-members or wheels. Embracing 90 the pin 10 is a coiled spring 17 with one end entering a suitable aperture in the presser-arm 8 and its other end entering an aperture in the hat-disk sustaining bracket or support 11, the spring retaining the bracket 11 with 95 its hat-supporting disk 16 in retracted or lower position with respect to the presser-member 7 and feed-member 6. In order to adjust the hat-supporting disk 16 with respect to the presser- and feed-members, a 100 thumb-screw 18 is provided, which enters a threaded aperture in a lug 19 formed on the presser-arm 8, the end of the thumb-screw 18 bearing against a suitable lug of the bracket 11. By turning the thumb-screw, 105 the bracket 11 is adjusted about its pin 10 against the stress of the spring 17.

Secured to the laterally projecting arm

20 of the lever 13, by suitable fastening screws 21, is the segmental guide-plate 22 extending to a point adjacent to the hat-supporting disk 16 at the stitching point.

- 5 In order to retain the hat-supporting disk 16 and segmental guide-plate 22 in operative position between the adjacent presser- and feed-members, the lever 13 is provided with a lateral arm 23 whose upper face is formed 10 with a shoulder 24 adapted to be engaged by the latch 25 adjustably secured by the fastening screw 26 upon the operating handle-lever 27 journaled upon the screw-stud 28 entering the bracket or support 11. The 15 latch 25 is spring-pressed against the lug of the lever 13 by means of the coiled spring 29 embracing the screw-stud 28 with one end 30 entering a suitable aperture in the lever-handle 27 and its other end resting against 20 a lug 31 on the bracket 11. Formed integral with said handle is a projecting pusher-finger 32 adapted to engage the under face of the shoulder 24 of the lever 13 and thereby force the lever, with its hat-supporting disk 25 16 and segmental hat-guide 22, out of operative position as shown in dotted lines in Fig. 1, to provide a clear space between the feed- and presser-members for the introduction of a hat. Entering the lug 31 is a screw 33 30 forming an adjustable stop for the lever 13 when in operative position, the screw 33 being locked in any desired position of adjustment by the jam-nut 34. When the hat-supporting disk 16 and segmental hat-guide 22 35 are out of operative position, the arm 20 of the lever 13 rests upon a support comprising a leather buffer 35 secured by a fastening screw 36 to a lateral spring-arm 37 carried by, and fastened by screws 38 to, the presser-arm 8. 40 Secured to the presser-arm 8, near the bed-plate 2, by the screw 39 is a downwardly extending arm 40 forming a support for the pivot-pin 41 clamped therein by the fastening screw 42. Journaled upon the pin 41 is 45 a rocker in the form of a bell-crank 43 whose upwardly extending arm 44 is entered by a screw-stud 45 embraced by one end of a bent link 46 whose other end has a pivotal connection, by means of the screw-stud 47, with 50 the lateral arm 23 of the lever 13. The other arm 48 of the rocker 43 is suitably apertured to receive a link or chain 49 adapted to be operatively connected with a knee- or treadle-plate (not shown).
- 55 When it is desired to begin a stitching operation the lever-handle 27 is depressed to release the latch 25 from contact with the shoulder 24 of the lever 13 carrying the hat-supporting disk 16 and segmental hat-guide 60 22, the pusher-finger 32 of the operating handle-lever forcibly shifting the lever 13, with the parts carried thereby, out of operative position and into retracted position, as shown by dotted lines in Fig. 1, so as to provide a clear space between the presser- and

feed-members. These members are normally maintained in yielding contact but may be separated for introduction of the work by devices shown and described in my patent application above referred to.

70 When the work has been introduced between the presser- and feed-members, the hat-supporting disk and segmental hat-guide are swung upwardly into operative position by actuating the knee- or foot-plate connected with the rocker 43. As the disk is moved into operative position by actuating a knee- or foot-plate, the operator's hands are left free to handle the work and properly adjust it for the stitching operation.

75 The operating handle-lever with its latch and pusher-finger constitutes a common element for retaining the disk 16 with hat-guide 22 in operative position and for positively insuring their movement out of stitching position when it is desired to introduce or remove the work.

80 Having thus set forth the nature of the invention, what I claim herein is:—

1. In a hat sewing machine, the combination with stitch-forming mechanism, of opposed feed- and presser-members, a hat-supporting disk having its periphery in a plane intermediate said feed- and presser-members, and means for moving said hat-supporting disk into and out of operative relation with said stitch-forming mechanism.

90 2. In a hat sewing machine, the combination with stitch-forming mechanism, of opposed feed- and presser-members, a hat-supporting disk, a support therefor movable in a plane intermediate said feed- and presser-members, and means for maintaining said disk in operative position.

100 3. In a hat sewing machine, the combination with stitch-forming mechanism, of opposed feed- and presser-members, a hat-supporting disk adapted for movement in a plane intermediate said feed- and presser-members, and means for retaining said hat-supporting disk in operative position and for positively moving it out of operative position.

110 4. In a hat sewing machine, the combination with stitch forming mechanism, of opposed feed- and presser-members, a hat-supporting disk having its periphery in a plane intermediate said feed- and presser-members, a segmental hat-guide mounted adjacent to and in coöperative hat-supporting relation with said disk, and means for moving said hat-supporting disk into and out of operative position.

120 5. In a hat sewing machine, the combination with stitch forming mechanism, of opposed feed- and presser-members, a hat-supporting disk having its periphery in a plane intermediate said feed- and presser-members, a segmental hat-guide mounted adjacent to and in coöperative hat-support-

ing relation with said disk, and means for moving said disk and hat-guide into and out of operative position.

6. In a hat sewing machine, the combination with stitch forming mechanism, of opposed feed- and presser-members, a hat-supporting disk having its periphery in a plane intermediate said feed- and presser-members, a carrier for said disk, means for moving said disk into and out of stitching position, and a support for said carrier when said disk is out of stitching position.

7. In a hat sewing machine, the combination with stitch forming mechanism, of opposed feed- and presser-members, a hat-supporting disk adapted for movement toward and from said stitch-forming mechanism in a plane intermediate said feed- and presser-members, and means for moving said disk from retracted into operative position.

8. In a hat sewing machine, the combination with stitch forming mechanism, of opposed feed- and presser-members, a hat-supporting disk adapted for movement toward and from said stitch-forming mechanism in a plane intermediate said feed- and presser-members, and means including a rocking element carrying a latch and pushing finger for releasing and shifting said disk from operative into retracted position.

9. In a hat sewing machine, the combination with stitch-forming mechanism, of a feed-member, a presser-member, a support therefor, a rotatable hat-supporting disk having its periphery in a plane intermediate said feed- and presser-members, and means carried by said support for moving said disk into and out of operative position.

40 10. In a hat sewing machine, the combination with a frame, stitch-forming mechanism mounted thereon, of a feed-member, a presser-member, a presser-arm mounted upon said frame and sustaining said presser-member, a support adjustably mounted upon said presser-arm, a lever fulcrumed upon said support, a hat-supporting disk sustained by said lever and disposed with its periphery in a plane intermediate said feed- and presser-members, and a latch for retaining said hat-supporting disk in operative position.

11. In a hat sewing machine, the combi-

nation with a frame, stitch-forming mechanism mounted thereon, of a feed-member, 55 a presser-member, a presser-arm mounted upon said frame and sustaining said presser-member, a support mounted upon said presser-arm, a lever fulcrumed upon said support, a hat-supporting disk sustained 60 by said lever and disposed with its periphery in a plane intermediate said feed- and presser-members, a latch for retaining said hat-supporting disk in operative position, and means carried by said latch for positively moving said hat-supporting disk out 65 of operative position.

12. In a hat sewing machine, the combination with a frame, stitch-forming mechanism mounted thereon, of opposed feed- and 70 presser-members, a presser-arm mounted upon said frame and sustaining said presser-member, a lever fulcrumed upon said presser-arm, a hat-supporting disk carried by said lever with its periphery in a plane 75 intermediate said feed- and presser-members, a rocker sustained by said presser-arm, and a connection between said lever and rocker for moving said hat-supporting disk into operative position.

13. In a hat sewing machine, the combination with a frame, stitch-forming mechanism mounted thereon, of opposed feed- and presser-members, a presser-arm mounted upon said frame and sustaining said presser-member, a lever fulcrumed upon said presser-arm, a hat-supporting disk and segmental hat-guide carried by said lever with the periphery of the disk in a plane intermediate said feed- and presser-members, a 90 rocker journaled upon said presser-arm, and a connection between said lever and rocker for moving said hat-supporting disk and segmental hat-guide into operative position.

14. In a hat sewing machine, the combination with stitch-forming mechanism, of opposed feed- and presser-members, a hat-supporting disk adapted for movement toward and from said stitch-forming mechanism in a plane intermediate said feed- and 100 presser-members, and means for adjusting the operative position of said hat-supporting disk.

In testimony whereof I have signed my name to this specification.

ALFRED GRIEB.
